(57) **CLAIM**

The ornamental design for a dispensing closure with hinged lid, as shown and described.

DESCRIPTION

FIG. 1 is a rear perspective view of a dispensing closure with hinged lid, said lid being in an open position, embodying our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and

FIG. 7 is a bottom plan view thereof; and,

FIG. 8 is a rear perspective view of a dispensing closure with hinged lid, said lid being in a closed position, embodying our new design.

The broken lines in FIG. 8 are included for the purpose of illustrating a portion of the dispensing closure with hinged lid that forms no part of the claimed design.
